APPARATUS FOR HONING

Hector R. Berard and William D. McKeon, Worcester, Mass., assignors to The Heald Machine Company, Worcester, Mass., a corporation of Massachusetts

Application November 5, 1936, Serial No. 109,330

6 Claims. (Cl. 51—34)

The present invention relates to an apparatus for honing, and especially to a device by which a short relative axial reciprocation between the hone and the workpiece may be produced during the honing operation.

In order to avoid the formation of circumferential scratches on the surface of the work being honed, it is desirable to impart to either the hone or the workpiece a short axial reciprocation which will break up or eliminate the honing lines, or in certain instances, will produce the familiar herringbone marks which frequently, when desired, characterize a honing operation. The relative reciprocation has in general been provided by mounting either the workpiece or the hone on a machine base on which is provided a reciprocating table, with the movements of the table providing the relative reciprocation. This machine arrangement is entirely satisfactory in operation, but it necessitates a relatively complicated table controlling and reversing mechanism which inevitably results in a high priced machine. One of the principal objects of the present invention is to provide for a relative axial reciprocation between the hone and the workpiece by an extremely simplified arrangement, with a provision for adjusting the length of the reciprocatory movement of the hone when desired.

Where the familiar herringbone appearance of a honed surface is to be produced, it is essential that the reciprocations of the hone be in predetermined relation to the relative relation between the hone and the workpiece so that the honing lines produced will have the herringbone appearance characteristic of a honed surface. These honing lines, which can readily be eliminated, are sometimes intentionally produced to increase the salability of the workpieces. A further object of the invention is accordingly to provide for a relative reciprocation between the hone and a workpiece in timed relation to the relative rotation thereof.

In a copending application of Blood, Serial No. 109,331, filed November 5, 1936, is disclosed a structure by which the spindle carrying the hone is reciprocated independently of the rotation thereof. In the present instance the reciprocation of the hone relative to the honing head is provided in response to the rotation of the spindle carrying the hone. In certain aspects the present invention is a modification of that disclosed in the Blood application above referred to.

A further feature of the invention resides in the provision of a single drive mechanism for

the relative rotation of the hone and work and the relative reciprocation therebetween. In accordance with this feature of the invention the hone is rotated and the reciprocatory mechanism is actuated in response to the hone rotation. 5

Other and further objects and advantages of the invention will more fully appear from the following detailed description taken in connection with the accompanying drawing, in which

Fig. 1 is a front elevation of a honing spindle 10 embodying the invention, with parts broken away to show the construction more clearly.

Fig. 2 is a side elevation of a fragmentary part of the device of Fig. 1, looking in the direction of the arrow 2 of Fig. 1. 15

Like reference characters refer to like parts in the different figures.

With reference first to Fig. 1, the hone, which may be of any suitable character, corresponds preferably to the hone disclosed in a copending 20 Blood application, Serial No. 69,861, filed March 20, 1936. It is sufficient to note, for the purpose of this application, that the hone comprises a head or arbor 1 having an axial bore 2, in which a hone spindle 3 is slidable. The arbor has a 25 key, not shown, to hold the spindle against rotation, but to allow for axial movement of the spindle. The spindle has an arcuate shoulder 4 positioned within the arbor, and the end of the spindle projects beyond the arbor and has a cap 30 5 secured thereto. The opposite end of the spindle receives an axially positioned bolt 6 for controlling the effective length of the spindle, the bolt being held against turning movement by a locking nut 7. A radial flange 8 on the head 35 provides for attachment of said arbor to the hone supporting and rotating mechanism, hereinafter described. The spindle 3, as shown, is made up of two separate members, but these members are functionally integral and are so 40 described.

The arbor 1 has a plurality of radially extending slots 9, in each of which is positioned a lever 10 substantially of bell crank form. Surrounding the arbor 1 adjacent the bases of the slots 9, is an 45 annular member 11 in threaded engagement with the outside of the arbor 1. The annular member 11 has an inwardly extending flange 12 spaced from the base of the slots 9 to receive one end of each bell crank lever 10 between said flange and 50 the arbor. This end of the lever has an arcuate surface 13 engageable with the flange 12 for rocking movement of the lever relative thereto.

The opposite end of the lever has an arcuate lug 14 engageable in an arcuate recess 15 in a 55

hone carrier 18. On the outer side of each of the carriers 18 is positioned a holder 17 in the form of a plate, to which is secured, as by a suitable adhesive, a honing member in the form of a stone 19, preferably of abrasive material. The stone is additionally held in place by flanges 18 extending outwardly from the holder.

The holders 17 are retained against the carriers 18 by coil springs 20 and 21, each arranged in the form of an annulus. The spring 20 is positioned at the inner or left hand (Fig. 1) end of the holders and engages the flanges 19. The other coil spring 21 is positioned in a recess 22 in the outer end of each of the holders, and the inturned portion of each holder which forms this recess, engages in a correspondingly shaped recess 23 in the carrier. For additionally holding the levers 10 in position, a coil spring 24, also in the form of an annulus, is positioned in a slot 25 in the arbor for engagement with all of the levers. At the corner of each bell crank lever is an arcuate protuberance 26, engageable with the arcuate shoulder 4 on the spindle.

The hone above described is mounted on the end of a hollow shaft 27 journaled in a housing 28, the shaft being driven in any suitable manner through pulleys 29 secured to the end of the shaft opposite to the hone. Within the shaft is an axially slidable rod 30, having a head 31 at the right hand end thereof engageable with the end of the bolt 6, and a coil spring 32 surrounding said rod normally urges said rod to the right (Fig. 1) for expanding the hone. Movement of the rod is limited by a nut 33 on the threaded left hand end of the rod, said nut being engageable with the end of the shaft 27. The nut 33 may be arranged for automatic adjustment on the rod 32 in the manner disclosed in the copending application of Blood, Serial No. 100,911, filed September 15, 40 1936.

The above structure is all fully described and claimed in earlier applications and is not of itself the present invention. The latter involves the attainment of the objects and novel features, 45 above outlined, in connection with the above or similar honing machine elements. In accordance with the present invention, the hone is reciprocated in response to the rotation of the shaft 27 on which the hone is mounted, so that the reciprocation and rotation of the hone occur in timed relation to each other.

With reference again to the drawing, the flange 8 of the hone arbor is secured, as by bolts 34, to a disk 35 having a hub 36 axially slidable on the right hand end of the spindle 27 and held against turning movement thereon by a key 37. The hone is thus reciprocable on the end of the shaft 27.

Secured to the housing 28 in axial alignment with the shaft 27 is a ring gear 38, which meshes 55 with pinions 39 journaled in a carrier 40 suitably secured against turning movement on the shaft 27 as by the threaded collar 41. Each pinion 39 has integral therewith a projecting stud 42 on which the pinion rotates in response to rotation 60 of the shaft 27. Each pinion also has a slot 43 (see also Fig. 2) having a stud 44 adjustably positioned therein. The stud 44 with its head 45 in the slot 43 has a sleeve 46 thereon which is held against the pinion by a nut 47 on the end of the 65 stud, thus locking the stud against movement on the pinion, although providing for adjustment thereon when desired. On the sleeve 46 is journaled an arm 48 on the end of which is a projecting pin 49 engageable in a recess 50 in the periphery of the disk 35.

As the shaft 27 rotates within the bracket, the pinions 39 are rotated on their axes, and since the pins 44 are offset relative to the axes of rotation of the pinions, a reciprocation of the disk 35 is produced with a corresponding axial reciprocation of the hone.

The workpiece *a* on which the honing is performed is mounted in a work-support 51 of any suitable character, and is held against rotation therein, during the honing operation. It will be apparent that the workpiece surface and the honing stones have corresponding tapers so that the entire inner surface of the workpiece is honed to the desired finish. In operation, the workpiece being in the operative position shown, the hone is 15 rotated by a rotation of the shaft 27. Since the ring gear 38 is stationary, the rotation of the shaft 27 procures a reciprocation of the hone which is necessarily in timed relation to the hone rotation. As the hone reciprocates on the shaft 27, the 20 spring 32 expands and contracts to hold the honing stones in honing position, and the spring 32 also expands and contracts to allow expansion and contraction of the hone as a result of the taper of the workpiece. The result is only a small 25 expansion and contraction of the spring 32 so that the honing stones exert a substantially uniform pressure on the workpiece during the entire honing operation.

From the foregoing it will be apparent that 30 the present invention provides for a reciprocation of the hone relative to the supporting structure by means of mechanism actuated by the hone rotation. The structure by which this reciprocation is procured is relatively simple and can 35 be arranged to provide the desired amount of reciprocation by adjusting the amount that the studs 44 are offset from the axes of rotation of the several pinions. The relative reciprocation between the hone and the workpiece is thus in 40 timed relation to the relative rotation therebetween. Moreover, the single driving means which produces the hone rotation also provides for the reciprocation thereof. It will be understood that the provision for reciprocation and rotation of the 45 hone may be applied equally well to other forms of cutting tools where a simultaneous rotation and reciprocation of the tool relative to the workpiece is desired, as for example, in internal grinding machines.

We claim:

1. In a honing device, a head, a spindle mounted for rotation within the head, a hone comprising a plurality of honing elements movable relative to each other for expanding and contracting the hone, a carrying member axially slidable on the end of the spindle on which the hone is mounted, means within the spindle for urging the honing elements into operative position, and means for reciprocating the carrying member and hone relative to the spindle and head in response to rotation of the spindle.

2. In a honing device, a head, a spindle mounted for rotation within the head, a hone comprising a plurality of honing elements movable relative to each other for expanding and contracting the hone, and means positioned within the spindle and movable axially of the hone for procuring expansion and contraction of the honing elements, a carrying member axially slidable on the spindle on which the hone is mounted, and means carried by the spindle and head for procuring a reciprocation of the carrying member relative to the spindle in response to rotation of the spindle.

- 5   3. In a honing device, a head, a spindle jour-
nalled therein, a hone positioned on the end of
the spindle and axially slidable thereon, a pinion
carried by the spindle and rotatable on an axis
at right angles thereto, a gear on the head with
which the pinion engages, and an eccentric as-
sociated with the pinion and connected to the
hone for procuring a reciprocation of the hone
in response to rotation of the spindle.
- 10   4. In a honing device, a head, a spindle jour-
nalled therein, a hone positioned on the end of
the spindle and axially slidable thereon, a pinion
carried by the spindle and rotatable on an axis
at right angles thereto, a gear on the head with
which the pinion engages, and an eccentric as-
sociated with the pinion and connected to the
hone for procuring a reciprocation of the hone
in response to rotation of the spindle, said eccen-
tric being adjustable relative to the axis of the
pinion for varying the length of the reciprocatory
stroke of the hone.
- 15   5. In a honing device, a head, a spindle jour-
nalled therein and supported against reciproca-
tion relative thereto, an expandible hone, means
carried by the spindle for procuring expansion
of the hone into operative position, means co-
operating with the spindle for controlling the
operative expanded position of the hone, a carry-
ing member reciprocable on the end of the spindle
and on which the hone is mounted, and an inter-
connection between the spindle and the carrying
member for procuring a reciprocation of the
carrying member and hone without a corre- 15
sponding reciprocation of the spindle.
- 20   6. In a honing device, a head, a spindle jour-
nalled therein and supported against reciproca-
tion relative thereto, an expandible hone, means
carried by the spindle for procuring expansion
of the hone into operative position, a carrying
member reciprocable on the end of the spindle
and on which the hone is mounted, and an inter-
connection between the spindle and the carrying
member for procuring a reciprocation of the
carrying member and hone without a corre- 20
sponding reciprocation of the spindle.
